(57) **CLAIM**

The ornamental design for a scoop holder as shown and described.

DESCRIPTION

FIG. 1 is a perspective view of a first embodiment of a scoop holder, showing our new design;

FIG. 2 is a perspective view of a second embodiment of a scoop holder, showing our new design;

FIG. 3 is another perspective view of the scoop holder of FIG. 2;

FIG. 4 is a front view of the scoop holder of FIG. 2;

FIG. 5 is back view of the scoop holder of FIG. 2;

FIG. 6 is left side view of the scoop holder of FIG. 2;

FIG. 7 is right side view of the scoop holder of FIG. 2;

FIG. 8 is a top view of the scoop holder of FIG. 2;

FIG. 9 is a bottom view of the scoop holder of FIG. 2; and, FIG. 10 is a perspective view of a third embodiment of a scoop holder, showing our new design in an environment of use.

The scoop holder is shown with a symbolic break in the structure in FIGS. 1-7. The appearance of any portions of the scoop holder between the broken lines forms no part of the claimed design.

The broken lines of FIG. 10 illustrate the environment and form no part of the claimed design.
